HOLDER FOR ABRASIVE MATERIAL

Wade Lamb and Carl W. Hood, Detroit, Mich.

Application May 30, 1945, Serial No. 596,624

4 Claims. (Cl. 51—187)

1

Our invention relates to holders for abrasive material such as sand or emery coated cloth or paper. Such material is used for a wide variety of purposes, but in all of such uses, the abrasive coating eventually becomes worn away, or becomes filled with particles of the material being abraded.

It is an object of our invention to provide a holder from which a strip of such abrasive material may be fed from a roll mounted within the holder, to present unused portions of the strip as the abrasive coating thereon becomes worn away or becomes filled with particles of the material being worked upon, the used portions of the strip being wound upon another roller also mounted within the holder. This feeding-out action of the unused portion of the abrasive strip, and the winding up of the used portion is brought about by turning a knob located on the side of the holder.

Another object of the invention is to provide a holder for abrasive material which has a handle portion at one end, and a tapered projection at the other end over which the abrasive strip is drawn. This produces a device which somewhat resembles a file in shape, and which may be operated by hand in much the same manner as a file or abrasive stone would be.

A further object is to provide such a holder wherein the roll of unused abrasive strip and the roller upon which the used portions of the strip are wound are both contained in a housing portion located in the central part of the holder, and this housing portion is so constructed that it may be readily taken apart to permit removal of the roll of used abrasive strip when all of the strip has been consumed, and easy insertion of a new roll of abrasive strip.

The above and other objects of the invention will be more readily understood by referring to the specification and accompanying drawing, in which:

Fig. 1 is a side elevational view of our improved holder for abrasive material, with portions broken away to show some of the interior construction;

Fig. 2 is a sectional view, taken on the line A—A of Fig. 1; and

Fig. 3 is a view somewhat similar to Fig. 1, but showing a slightly different model of abrasive holder embodying the invention.

The reference numeral 10 indicates a housing portion having a recess 12 formed therein, which recess is preferably of rectangular shape. 14 is a 55

2

handle portion which is shown as being formed as an integral part of the housing, but it may of course be made as a separate part, if desired, and be secured thereto in any suitable manner. 16 is a cover which serves to close the open end of the housing, and this cover carries two spaced apart walls 18 and 20, which are of such dimensions that they are adapted to fit snugly within the recess 12. Screws 22, or other suitable securing members, extend through holes in the sides of the housing and are threaded into the walls 18 and 20 to hold the cover in position on the housing.

Extending outwardly from the cover 16 is a projection 24 which is tapered so that it is of reduced thickness at its outer end. Adjacent the point where the projection joins the cover, at one side thereof there is formed an elongated aperture or slot 26, while at the other side there is formed another slot 28, both of which extend through the cover and communicate with the interior of the housing when the cover is in place thereon.

Each of the walls 18 and 20 has slots 30 and 32 formed in them, these slots extending inwardly into the walls from the outer ends thereof. Rotatably supported in the slots 28 in the walls 18 and 20 is a roller 34 upon which is carried a roll 36 of abrasive material in the form of a strip 38 which may be of paper or cloth, coated with sand, emery dust, carborundum particles, or any other desired abrasive material. The roll 36 is located in the space between the walls 18 and 20 which keeps it in proper position on the roller 34. The strip 38 is fed out through the slot 26 and extends over the end of the projection 24 and back on the opposite side thereof and then through the slot 28 where it is secured to another roller 40 which is rotatably supported in the slots 32 in the walls 18 and 20.

The roller 34 with the roll 36 mounted upon it and the roller 40 are assembled in position in the slots 30 and 32 in the walls 18 and 20 while the cover is removed from the housing. Thereafter the cover is placed over the housing so that the walls 18 and 20 fit into the recess, the outer edge of the cover bearing against the edge of the housing to limit such inward movement, and then the screws 22 are placed in position to hold the parts in assembled relation.

One end of the roller 40 projects beyond the wall 18 and is adapted to slide through a slot 42 in the side wall of the housing portion 10 when the cover is being assembled in position on the

housing. On this projecting end of the roller 40 is secured a knob 44. The holder is now ready for use.

It may be used in substantially the same manner and for the same purposes as a file or abrasive stone would be used, to smooth or abrade away portions of wood, metal or any other material, the portion of the strip 38 on either side of the projections 24 being available for this purpose. When as a result of such use, the abrasive coating becomes worn away or filled with particles of the material being worked upon, so that it is no longer useful, the knob 44 is turned in a direction which will cause the strip 38 to unwind from the roller 34 and slide around the end of the projection 24 and become wound upon the roller 40, thus presenting an unused section of the abrasive material.

The rollers 34 and 40 are of such diameter that they fit snugly within the slots 30 and 32, which results in their being held firmly in position therein, so that they do not rotate until the knob 44 is turned. This causes the strip 38 to be held tightly in position upon the projection 24. If desired, any suitable spring tension means could be employed to positively hold the rollers in position in the slots 30 and 32 until it is desired to move them, but it is not believed that such means will be necessary.

At the outer end of the projection 24, there is provided at each side a small plate 46, which is secured to the projection by a fastener 48. These plates serve as guides to hold the strip of abrasive material in proper position laterally on the projection, and also to protect the end of the abrasive holder from damage should it accidentally come into contact with the work or should it be dropped.

When after considerable use, all of the strip of abrasive material has been unwound from the roller 34 and wound upon the roller 40, the screws 22 are removed so that the holder can be taken apart, and these rollers and the used abrasive strip are removed, and new rollers, one of which has a fresh abrasive strip wound thereon, are inserted, after which the device is reassembled ready for further use.

Abrasive holders of this type are useful not only in shops or other places where files or abrasive stones are ordinarily employed, but may also be used for many other purposes such as by draftsmen or artists as sandpaper upon which pencils or crayons may be pointed, or as abrasive sticks for smoothing finger nails or for any other use for which abrasive sticks are ordinarily employed. When used for the latter purposes, the holder would be made smaller and lighter, such a form of holder being shown in Fig. 3, wherein the same reference characters are used to refer to the parts, which are similar in design to those shown in Figs. 1 and 2. In this form it will be seen that the strip 38 is made narrower in proportion to the length of the holder, and the handle portion 14 is made somewhat smaller.

While we have shown and described specific forms of our invention, it will be understood that various changes in size, shape and details of construction may be made without departing from the spirit and scope of the appended claims.

We claim:

1. In a holder for abrasive material, the combination of a housing having an open end and a handle portion, a cover for the open end of said housing, a projection extending outwardly from

the cover, having a pair of slots extending through the cover on opposite sides of the projection, a strip of abrasive material extending outwardly from the interior of the housing through one of the slots, said strip being supported on said projection and extending over the end thereof and back on the opposite side and thence into the interior of the housing through the other of the slots, a pair of rollers carried by said cover located within the housing, the opposite ends of the strip each being connected to one of said rollers, and means accessible from the exterior of the housing operable to rotate one of said rollers whereby said strip will become wound upon that roller to advance an unused portion of said strip into position upon the projection.

2. In a holder for abrasive material, the combination of a housing having an open end and a handle portion, a cover for the open end of said housing, a flat elongated projection extending outwardly from the cover, having a pair of slots extending through the cover on opposite sides of the projection, a strip of abrasive material extending outwardly from the housing through one of the slots, said strip being slidably supported upon the projection and extending over the end thereof and back on the opposite side and thence into the housing through the other of the slots, and guide means located at each side of the projection and extending therebeyond, said guide means serving to hold said strip in position laterally on said projection.

3. In a holder for abrasive material, the combination of a housing having an open end and a handle portion, a cover for the open end of the housing, a flat elongated projection extending outwardly from the cover, said cover being provided with an aperture located at each side of the projection, a roller rotatably supported on the cover inside of the housing, a strip of abrasive material wound upon said roller, the outer end of said strip extending outwardly through one of said apertures and being supported upon said projection and extending over the end thereof and back on the opposite side and thence into the housing through the other of said apertures, a second roller rotatably supported on the cover and having a portion projecting outside of said housing, a knob secured to the outer end of the second roller, the end of said strip being connected to said second roller so that as the latter is rotated by the knob, the strip will become wound thereupon causing unused portions of said strip to be moved into position upon said projection.

4. In a holder for abrasive material, the combination of a housing having an open end and a handle portion, a cover for the open end of the housing, a flat elongated projection extending outwardly from the cover, said cover being provided with an aperture located at each side of the projection, two spaced walls extending from the cover into the housing having slots formed therein, a roller rotatably supported in one of the slots in each wall, a strip of abrasive material wound upon said roller in the space between said walls, the outer end of the strip extending out through one of said apertures and being supported upon the projection and extending over the end thereof and back on the opposite side and thence into the housing through the other of said apertures, a second roller rotatably supported in the other of said slots in the walls and having a portion projecting outside of said housing, a knob secured to the outer end of said second roller, the end of said strip of abrasive material being connected to the

second roller so that as the latter is rotated by the knob, the unused portions of the strip will become unwound from the first mentioned roller and the used portions of the strip will become wound upon said second roller.
